FIG. 4

INVENTOR

EDWARD B. BIRKENBEUEL

UNITED STATES PATENT OFFICE.

EDWARD B. BIRKENBEUEL, OF PORTLAND, OREGON.

JAR-SEAL TESTER.

1,340,473.

Specification of Letters Patent. Patented May 18, 1920.

Application filed March 20, 1919. Serial No. 283,781.

To all whom it may concern:

Be it known that I, EDWARD B. BIRKENBEUEL, a citizen of the United States, and a resident of Portland, county of Multnomah, 5 and State of Oregon, have invented a new and useful Jar-Seal Tester, of which the following is a specification.

My invention relates more particularly to that class of fruit jars having a more or 10 less flexible cap, and to a means for testing the state of preservation of their contents.

The object of my invention is to render it possible to determine the condition of the contents of a jar by simply moving the 15 tester across the cap.

It is a commonly known fact that the caps are held on fruit jars by a reduction of the internal pressure through cooling, and that the pressure thus exerted on the 20 cap causes it to be bent toward the inside of the jar, thereby presenting a concave face to the outside. The lower the pressure within the jar the greater will be the degree of curvature of the cap. To utilize 25 this condition I have constructed my device as follows:

Referring to the drawing. Figure 1 is a plan of the device showing the manner of application; Fig. 2 is an elevation showing 30 a jar with a poor seal and a flat cap; Fig. 3 is an elevation showing a perfectly sealed jar with the cap bent inward; Fig. 4 is a perspective view of my device with a portion cut away to show the scribing point.

Like letters and number of reference refer to the same or similar parts throughout the several views.

Referring in detail to the drawing. J^1 represents the ordinary glass fruit jar 40 which is closed by the cap C^1 , the body or center of which I shall designate as C^2 . It will be noticed that the portion C^2 is not backed up by a thickness of porcelain as is customary in some types of fruit jars, to 45 which my device is not applicable.

The elements of my jar seal tester consists of a flat frame member T^1 the ends of 50 which are turned down to form the stops T^2 which have a distance between them somewhat greater than the outside diameter of the fruit jar cap. Midway between the stops T^2 , and extending in the same direction, is the sharpened scribe point S^1 which has a tapered body S^2 which fits into a 55 corresponding hole in the bar T^1 and it is riveted thereto at S^3 .

The operation of my device is as follows: After food has been placed in the jars for the purpose of preserving same, it is ordinarily a simple matter to detect jars with 60 imperfect seals, but oftentimes, due to imperfect sterilization, chemicalization takes place which will destroy the seal, and the contents of the jar may be lost. Since the cap may adhere tightly to the jar in spite of 65 an imperfect seal, the adhesion test is by no means reliable.

By placing my tester on a jar in question, as shown in Fig. 2, it will be seen that the scribe point S^1 rides on the cap body C^2 , 70 and any movement of the tester with a slight downward pressure will mark the cap, thereby indicating a poor seal. If, however, the cap body C^2 is depressed by the atmospheric pressure, the tester will 75 ride on the outer edge of the cap but the scribe points will not touch anything.

The simplicity and utility of my device are very apparent, when it is considered that a periodical testing of the caps will 80 enable anyone to select those jars whose contents are in a less perfect condition and use same before they have become unfit for food.

While I have thus illustrated and de- 85 scribed my invention, it is not my desire to limit myself to this precise form of construction or method of application of my device, but intend that it shall cover all forms and modifications that fall fairly 90 within the appended claims.

What I claim as new and desire to protect by Letters Patent of the United States, is:—

1. In a device for testing flexible metal 95 jar caps, a body member of a relatively rigid material having a flat bearing surface bounded by a pair of integral downwardly extending ends and having at a point midway between said ends a marking scribe 100 having a pointed tip extending below the bearing face of said bar.

2. In a device for testing flexible metal 105 jar caps, a body member having a downwardly extending portion at either end, said portions being spaced apart at a distance somewhat in excess of the diameter of the cap to be tested, and having a straight bearing surface for the top of the cap near each downwardly directed portion and having at 110 a central point a scribe the point of which lies at a fixed distance below the bearing

surfaces and in the direction of said downwardly directed portions.

3. In a device for testing jar caps of flexible metal, a body of relatively rigid material having a flat lower bearing face and having its two ends extending downwardly to form stops at a greater distance apart than the diameter of said flexible metal jar

cap, and a marker or scribe in fixed position on said body approximately midway between said ends and extending a fixed distance below the lower bearing face of said body and in the direction of said downwardly directed end portions. 10

EDWARD B. BIRKENBEUEL.
